MATCH BOOK MACHINE

Edwin J. Bell, Oshkosh, Wis., assignor to The Bell Machine Company, Oshkosh, Wis., a corporation of Wisconsin

Application May 6, 1935, Serial No. 20,027

18 Claims. (Cl. 164—49)

This invention relates to improvements in match book machines.

It is the primary object of the invention to improve the accuracy and speed of operation of a machine for the manufacture of match books. More specifically stated, it is my purpose to provide a magazine feed for the match combs from which the match blanks are cut; to provide a feed for advancing the combs to a fixed stop with which the cut-off knives are associated, whereby to ensure that each of the blanks will be accurate as to size; to provide an improved feed for the cover stock blanks to assure their accurate delivery through the folder to the point where the match comb blanks are assembled therein; to provide means for registering the comb blanks accurately with each cover blank following the assembly of the blanks; to provide improved automatic delivery mechanism for assembling the completed books in stacks and counting the books to divide the stacks into packages containing a predetermined number of books; and generally to provide in simple and compact form the operating connections for the actuation of the several parts in timed synchronism for the continuous production of match books.

In the drawings:

Figure 1 is a front elevation of a machine embodying the present invention, omitting those conventional portions thereof which relate to the application of striped paint to the otherwise complete books, and the subsequent drying of the paint.

Figure 2 is a plan view of the mechanism shown in Fig. 1.

Figure 3 is an enlarged detail view taken in section on the line indicated at 3—3 of Figure 1.

Figure 4 is a fragmentary plan view of one of the match book assembling units, there being two assembling units in the preferred embodiment of the machine.

Figure 5 is an enlarged detail view in transverse section on the line 5—5 of Figure 1.

Figure 6 is an enlarged view partially in front elevation and partially in section on the line 6—6 of Figure 4 showing a detail of the cut-off knife, friction feed rolls, and stop.

Figure 7 is a detail view in end elevation on an enlarged scale showing a portion of the ratchet feed for the magazine.

Figure 8 is a fragmentary detail in plan showing the feed member for the cover stock.

Figure 9 is a fragmentary detail taken in section on an enlarged scale through the device associated with the cover folder for finally registering the match comb blanks in the cover.

Figure 10 is a view showing in plan on an enlarged scale the stacking, counting and discharge mechanism.

Figure 11 is a fragmentary detail in side eleva-

tion of the cam actuated mechanism for operating the unloading fingers.

Figure 12 is a detail view taken in section on the line 12—12 of Figure 10.

Figure 13 is a detail view taken in section on the line 13—13 of Figure 10.

Figure 14 is a diagrammatic view showing the relative positions of some of the major portions of the apparatus.

Figure 15 is a detail view in perspective showing two superimposed match combs as supplied to the comb magazine.

Figure 16 is a similar view showing match book blanks severed from the combs of Fig. 3.

Figure 17 is a view in perspective showing the match comb blanks as they appear when inserted into the cover blank.

Figure 18 is a view in perspective illustrating the first step in folding the cover blank over the bases of the match comb blanks.

Figure 19 is a view in perspective showing the completion of the folding operation initiated in Fig. 15.

Figure 20 shows the folded over portion of the cover stock stapled through the bases of the comb blanks.

Figure 21 is a similar view in perspective showing the completed book to which the striker's paint has been applied.

Like parts are identified by the same reference characters throughout the several views.

I shall first refer to the general organization of the machine and follow this with detailed description of the component parts pertinent to the present invention.

The previously manufactured match combs are inserted in pairs as in Fig. 15, into a magazine generically designated by reference character A and best illustrated in Figs. 1, 2, 3, 4 and 7. There are two such magazines in the apparatus as disclosed.

From each such magazine successive pairs of match combs are discharged and fed by a feeding and cut-off device generically designated by reference character B and best shown in Figs. 1, 2, 3, 4 and 6. In the feeding and cut-off device match book blanks of the nature shown in Fig. 16 are successively severed from the leading ends of the successively fed match comb pairs.

In the meantime the cover stock blanks piled in the cover stock magazines generically designated by reference character C (Figs. 1, 2, 4 and 5) are being delivered one at a time to folding mechanisms D (Figs. 2, 4 and 5) and a match blank feeder E (Figs. 4 and 5) periodically inserts each successive match blank into the folded cover stock and delivers these assembled parts in the condition shown in Fig. 17 to the conveyor chain F.

Without at this time describing in detail the

operations of completing the book, it will be sufficient to state that the comb blanks are now accurately registered in folded covers, the covers are folded over the registered blanks and stapled or stitched, and the striker paint is applied by means which is conventional and hence is not here illustrated.

Thereafter the chain includes several flights to and fro upon which the striker paint is allowed to dry, these flights also being conventional and not here illustrated, and finally the chain returns the finished product to the discharge portion of the machine where the unloader and stacking mechanism generically designated by reference character G (Fig. 1, 2 and 10) nests together the finished books, compacts them in a stack, and delivers counted units for packaging. The unloading point is immediately adjacent the point where the chain is again charged with assembled cover stock and match comb blanks.

Having indicated the general organization of the machine, I shall now describe its component sections.

25

The match comb magazine

This being a duplex machine, there are two match comb magazines. Inasmuch as they are identical, however, only one will be specifically described. The match comb magazine generically designated by reference character A, comprises a suitable support 1 extending upwardly from the bed 2 of the machine frame and provided with suitable bearings for the upper and lower sprocket shafts 3 and 4 respectively. These shafts carry sprockets 5 and 6 respectively, over which operate the spaced conveyor chains 7, each such chain being provided at corresponding intervals with outwardly projecting pegs at 8 constituting supports for pairs of match combs 9 (Fig. 15) which are laid thereon by the operator.

In a few minutes the operator may position a pair of match combs on each pair of corresponding pegs of the conveyor chains 7, and he is then free to attend to other work since the number of supports for pairs of combs is sufficient to enable the machine to function for a considerable period without further attention.

50 Ultimately in the progressive downward advance of the pegs 8 supporting pairs of match combs, such pegs pass through notches shown in dotted lines at 10 in Fig. 4 in the supporting plate 11 on which each successive pair of match combs is deposited as the pegs pass through the plate. Resting on plate 11 in a normally retracted position, are the pushers or ejectors 12 which, in the present device, are three in number. These ejectors are synchronously actuated by means hereinafter to be described to push the superposed match combs on to the feed table 15 with their butt portions engaged between the feed rolls 16.

65 The match comb feed and cut-off mechanism D

The feed rolls 16 constitute a part of the match comb feed and cut-off mechanism now to be described.

70 The feed rolls have tapered ends to facilitate the introduction of the match combs therebetween. The upper roll is mounted on a spindle 17 carried by a block 18 fulcrumed on a cross pin 19 and pressed into operative engagement with the other feed roll by means of the com-

pression spring 20 adjusted as to its compression by set screw 21. The feed rolls 16 are interconnected by gears 22 and 23 to rotate in unison.

As clearly appears in Fig. 4, there are two sets of the feed rolls 16 associated with that portion of feed table 15 on to which the match comb pair 9 is pushed by the ejectors 12. There are two other sets of feed rolls 25 near the right hand end of the feed table 15 as viewed in Fig. 4. These feed rolls correspond in general to feed roll 16 as to their mounting and inter-gearred connection.

The lower feed roll of each of the sets 16 and 25 carries a sprocket 26 (Fig. 3), the several sprockets being connected for uniform movement by a chain 27. This chain is actuated by the pawl 28 (Fig. 4) which engages the successive links of the chain and is pivoted at 29 to the arm 30 of lever 38, which lever is oscillated by means hereinafter to be described. The result of this arrangement is the intermittent advance of the chain and the corresponding intermittent rotation of the feed rolls 16 and 25 to advance along feed table 15 the match comb pairs engaged between the rolls. The rate of advance is somewhat faster than is required by the cutting of blanks from the leading edge of each successive match comb pair.

At the right hand end of feed table 15 as viewed in Fig. 4 and Fig. 6, is a shear blade 33 across which each match comb pair 9 is fed.

In the path of advance of the match comb pairs 9 is a stop arm 34 carried by a stop slide 35. The channel block 36 in which slide 35 is adjustable is engaged at its end by the knurled head 37 of the adjusting screw 38. In an ear 39 of block 36 is a set screw 40 which also engages the head 37 of the adjusting screw, whereby such head is confined against any axial displacement. Obviously, therefore, the rotation of the knurled head 37 will adjust the stop arm 34 very gradually in the path of movement of the paired match combs 9.

Coacting with the fixed shear blade 33 is a vertically reciprocable shear blade 42 carried by slide 43 (Fig. 6). This slide may conveniently be reciprocated from shaft 45 by means of an eccentric 46, eccentric strap 47, connecting rod 48, and wrist pin 49.

As above noted, the rate of feed of the match comb pairs 9 by the feed rolls 16 and 25 is in excess of the actual requirements of the machine. Thus, when the leading ends of the match comb pairs reach the stop arms 34 and the pairs are thereby brought to rest, the continued movement of the rolls results in the frictional slippage of the rolls on the butt surface of the combs. This holds the combs tightly to the stop and enables the cut of the shear knives 42 and 33 to be located with great accuracy between two consecutive matches on the respective combs. It has been found that any less accurate and less easily adjustable feed is unsatisfactory for the reason that there are changes in the length of the paper, whereof such combs are composed, such that other feeds do not definitely locate the cut between consecutive matches.

Since the movement of the comb engaged by rolls 25 is retarded by the repeated contact of its successively cut end portions with the stop arm 34, the rate of advance of this comb is retarded as compared with the comb freshly ejected from the magazine into engagement with feed rolls 16. Thus, although there is initially a substantial dis-

tance between the ends of the combs, that engaged by feed rolls 16 will rapidly overtake the free trailing end of the comb pair engaged by feed rolls 25, and thereupon the two comb pairs 5 will necessarily move in unison until the leading comb is completely cut up into blanks and the cutting of the successive comb pair is commenced. In practice, each of the comb pairs 9 shown in Figs. 4 and 12 is cut into ten equal 10 blanks. While the specific number is not important in any broad application of the invention, it is of consequence to the specific design of the machine disclosed, as will hereinafter appear.

It will, of course, be understood that in the 15 present machine there are not only duplicate comb magazines, but duplicate feed tables and duplicate cut-off knives. The blank feeders, cover stock magazines, and folders, hereinafter to be described, are also duplicated.

20 Driving connections for comb magazine A and comb feed and cut-off device B

The actuation of the cut-off knives 42 from shaft 45 as shown in Fig. 6, has already been described. The same drive shaft is provided at 50 (Fig. 3) with a cam operating upon a cam follower roller 51 carried by arm 52 pivoted to the under side of the machine table 2 and biased by a tension spring 53 to maintain the roll in contact with the surface of the cam.

On the end of arm 52 is a pawl 54 held by the tension of spring 55 in engagement with the teeth of a double ratchet comprising ratchet wheels 56 and 57. These ratchets are mounted on the shaft 58, to which the smaller ratchet 57 is made fast, the larger ratchet 56 being free to rotate. Four out of five teeth of the ratchet 56 are shallow, so that they support the pawl 54 out of engagement with the teeth of ratchet 57. Every 40 fifth tooth of ratchet 56, however, is cut more deeply as shown at 59 so that on each fifth operation of pawl 54 the pawl will approach sufficiently closely to shaft 58 to actuate the smaller ratchet 57 to the extent of one tooth.

Carried by shaft 58 is a gear 60 which drives the idler pinion and gear set 61 and thereby transmits motion to gear 62. This gear has a crank pin at 63 connected by link 64 with the ear 65 of a slide 66 having upstanding fingers at 67 engaging the pin 68 of one of the rocker arms 69 which support the ejector pawls 12 from rock shaft 70 (Figs. 3 and 4). The gear ratio is such that for each single tooth of advance of the gear 57 the crank disk 62 makes one half of a rotation, the ejector pawls 12 being either advanced or retracted, as the case may be. It being remembered that for every rotation of shaft 45 the cut-off knife is reciprocating to sever a blank, it follows that when ten such cuts have been made, thus using up one comb pair 9, the ejectors 12 will move forwardly to position another comb pair on the feed table 15.

The rock shaft 70 is provided with another arm at 71 connected by link 72 with the carrier 73 of pawl 74 which acts on the ratchet wheel 75 carried by shaft 3 of the comb magazine conveyor (Figs. 3, 4 and 7). This progressively moves the conveyor to deposit new comb pair 9 on the plate 11 each time the ejectors 12 are retracted following the discharge of one comb pair on to the feed table. In other words, the magazine conveyor is actuated only by the retractive movement of the ejectors.

The pawl 28 which actuates chain 27 for the 75 rotation of feed rolls 16 and 25 is driven, as afore-

said, by lever 18. This lever 18 is actuated by cam 19 and also serves to actuate the cover stock feed by means of link 80 as will hereinafter be described.

The cover stock magazine C

The cover stock magazine C comprises a chamber which is of generally well known construction. The cover stock blanks are piled therein as shown at 81 (Figs. 4 and 5). They are discharged from the magazine in a known manner by means of the cover stock feed slide 82, which is bifurcated to provide legs 83. This slide is actuated by the link 80 to reciprocate beneath the magazine C. The stack of cover blanks 81 is supported on the legs 83 of the feed slide, and these legs are shouldered at 84 (Fig. 8) to correspond to the thickness of one cover blank so that upon each reciprocation of the slide a single cover blank is ejected from the bottom of the magazine. 20

In order to facilitate the operation of the slide, the legs are preferably hollow and provided with vents at 85 connected through the hollow interior of the slide with a vacuum hose 86 which causes the lowest cover blank in the stack to adhere to 25 the slide for ejection in the manner described.

In the outermost position of the feed slide 82 the blank carried thereby rests across the folding table 87. The cover stock folder herein-after to be described includes an operating rock shaft 88 carrying an arm 89 from which the pin 90 projects. At each oscillation of the rock shaft the pin 90 strikes the head of a plunger 91 mounted in the side of the magazine and normally retracted by spring 92. At its inner end this plunger engages a false side or loose plate 93 of the magazine. By this novel arrangement the cover stock blanks 81 in the magazine are intermittently being vibrated and maintained in alignment during the operation of the machine. 40 Thus the magazine need not engage the cover stock blanks so tightly as to restrict their downward movement, and yet an absolute alignment of the blanks with reference to the feed slide and folder is assured.

The cover stock folder D

The folding table 87 is slotted at 95 in registry with an arcuate feed chute 96 concentric with the rock shaft 88. Adjacent the lower end of this chute its walls are notched at 97 and 98 to receive the shorter and longer ends respectively of the folded cover blank 99 (Fig. 5). Mounted on the rock shaft 88 is the arm 100 which carries the folding tucker blades 101. This blade operates through the delivery chute 96, as clearly shown in Fig. 5.

It will readily be understood by those skilled in the art that the rock shaft 88 rotates clockwise as viewed in Fig. 5 until the tucker blade 101 is elevated above table 87. At this time the single blank fed from the bottom of the magazine is projected across the table and beneath the blade. Thereupon the rock shaft 88 oscillates in a counter-clockwise direction as viewed in Fig. 5 to engage an intermediate portion of the blank, thereby forcing such intermediate portion to become folded and fed through the table slot 95 and the chute 96 to the ultimate position shown in Fig. 5. In Fig. 5 the blade is in the course of its retractive movement following the folding and feeding of the cover stock blank 99.

Match blank feeder E

Tangential to the arcuate cover chute 96 is 75

the channel 104 in which operates the slide 105 for feeding the previously severed match blanks 106. It will be recalled that the progressively fed match comb pairs have been stopped by the gauge 34 beneath the shear knife 42 and double match blanks severed therefrom by the descent of said shear knife across the shearing surface of the fixed blade 33. The double blanks thus severed are deposited in the channel 104 in the path of slide 105 of the mechanism E, such slide being then retracted. As the tucking blade which has folded the cover blank 99 is retracted from the blank the feed slide 105 is moving forwardly to insert the live ends of the paired match blanks into the fold of the cover stock as shown in Fig. 5.

The continued forward movement of the slide pushes the folded cover 99 as well as the match blanks into the grasp of the retaining clip 107 of the pocket member 108 carried by each link of chain F. The conveyor chain and the subsequent operations performed on the assembled blanks will hereinafter be described.

Actuating connections for the folding mechanism D and the match blank feeder E

The main drive shaft 45 which extends longitudinally of the machine carries the cam disks 111 and 112 and cam grooves 113 and 114 in their respective faces. The cam follower roller shown in dotted lines at 115 in Fig. 5 operates in the cam groove 113 and is mounted upon a lever 116 connected by link 117 to the arm 118 of rock shaft 88. This arrangement oscillates the rock shaft to tap the aligning plunger 91 of the cover stock magazine and to oscillate the tucking blade 101 of the cover stock folder and feeder designated generally by reference character D.

Operating in the cam track 114 of cam disk 112 is the roller 120 shown in dotted lines in Fig. 5 and mounted on a lever 121. Pivoted concentrically with lever 121 is the lever 122 connected by link 123 with the feed slide 105. A resilient connection is established between lever 121 and lever 122 by means of the threaded post 124 carried by lever 122, and the compression spring 125 encircling such post and confined between lever 122 and ear 126 on lever 121.

The engagement of the ear with the nut 127 on post 124 ensures the positive retraction of slide 105 while, in the opposite direction of movement, the thrust is transmitted through the compression spring 125 so as to provide for a certain degree of lost motion as the pair of match blanks and superposed cover 99 are thrust home into the pocket 108 of the conveyor chain.

The conveyor F and its actuating connections

In the preferred embodiment of the invention the conveyor F comprises a chain having links 130 (Fig. 4), each link carrying one of the receptacles 108 above referred to. From the right hand side of Figs. 1 and 2 to the left hand side of such figures, the conveyor F follows a circuitous path in the course of which the striker paint is applied to the otherwise complete match book and is dried thereon before the books are unloaded from the conveyor. This portion of the chain, being conventional, is not illustrated.

Separate means are employed for advancing the chain at different points according to the requirements of the apparatus. Adjacent each end of the main drive shaft 45 (Fig. 1) is a helical cam 131 coacting with the successive studs or teeth

132 of the crown wheels 133. The drive to the chain is illustrated only at the left hand side of the apparatus as viewed in Fig. 1 and Fig. 2. Crown wheel 133 is mounted on a shaft 134 which projects at the rear of the table and carries a sprocket 135 over which operates the driving chain 136 leading to sprocket 137 on shaft 138. Shaft 138 carries the main driving sprocket 139 over which the conveyor F passes, as shown in Figs. 1, 2, 4 and 10.

A similar sprocket 140 spaced to the left of sprocket 139 is an idler, and the chain passes over sprocket 140 and downwardly around a guide 141 and thence upwardly over sprocket 139 to provide a bight at the unloading stations hereinafter to be described. Passing to the right from sprocket 139 as viewed in Figs. 1, 2 and 4, the conveyor passes beneath an idler guide sprocket 143 and thence along the bed of the machine.

At the center of the machine there are two loading stations of which the disclosure of Fig. 5 is typical. At each of these stations the feed slide 105 is intermittently inserting a match comb blank into a cover stock blank and driving the assembled blanks together into receptacles 108 carried by the conveyor. Because there are two such stations the conveyor is made to move two steps in each operation, and the two stations are so located as to register with different alternate receptacles of the conveyor. It is obviously of some importance that the conveyor movements be controlled with accuracy adjacent the loading stations and accordingly, although the main conveyor drive takes place through the sprockets 139 as above described, I provide a more accurate pawl feed which takes up slack between the conveyor links and accurately positions the links at the loading stations.

The main drive shaft 45 carries a bevel pinion at 145 meshing with a gear 146 (Fig. 1). This gear drives shaft 147 (Fig. 2) from which a chain 148 actuates the stitching mechanism 149 which, being conventional, is not shown in detail. Shaft 147 also carries a crank 150 which transmits motion through connecting rod 151 to an oscillatory lever 152 pivoted to the rear of the bed of the machine and provided with a pawl 153 riding over the links of the chain and, upon each oscillation, engaging the upstanding lugs 154 of the several links to advance the chain two steps at each oscillation of the lever.

During each dwell in the advance of the chain, pressure is applied to the match comb blanks to force them home into the cover stock blanks and to seat both blanks in final registry with the receptacle 108 in which they have been placed. Immediately following this seating or registering operation, the folding is done. The mechanisms for performing these functions are shown in Fig. 9.

The main drive shaft 45 carries a double faced cam 156 having cam grooves 157 and 158 in its opposite faces. The levers 159 and 160 have cam follower rollers operating in the respective grooves 157 and 158 to operate the folding slides 160 and 161 respectively.

Mounted on slide 160 is an arm 163 having an apertured portion 164 loosely engaging the end of the lever 165 which is mounted on rock shaft 166. This rock shaft carries the registering blade 167 which is shown in the act of registering or thrusting the match blank 106 to its full depth into the cover blank 99 in the receptacle 108 before the forward movement of the chain carries

such receptacle to a position of registry with the folding slides 160 and 161. It will be understood that the arm 167 is offset toward the observer in Fig. 9 from the plane in which slide 160 is operative.

During the continued operation of the device, slide 160 will be advanced and blade 167 will thereby be retracted from engagement with the match blank, this operation being followed by the outward movement of the folding slide 161 which will turn upwardly the longer free edge of the cover blank 99. The free margin 168 of the cover blank 99 will now extend upwardly as shown in Fig. 18. In the next position of dwell of the conveyor chain the upturned margin 168 will be acted upon by the folding slide 160 which will turn it downwardly to its final position as shown in Fig. 19. In a subsequent position of the conveyor the stitcher will operate thereon to incorporate a stable or like securing device as shown in Fig. 20 to complete the book. As previously stated, the painter is conventional and accordingly is not illustrated.

The unloader G

It will be recalled that the returning flight of the conveyor F passes over sprocket 140 and thence downwardly along the guide 141 and upwardly to pass over sprocket 139, thus forming a bight at the unloading stations. One of these unloading stations is located where the downwardly descending flight of the conveyor F passes through the opening 175 in the machine bed. The other unloading station is located where the ascending flight of the conveyor F emerges from opening 176 in the machine bed. The arrangement is such that at each dwell of the conveyor chain alternately different receptacles 108 there-
40 of will be at the level of the machine bed or table at the respective unloading stations.

Leading from each unloading station is an arcuate match book guide or channel, the channel 177 being of shorter radius than channel 178. The delivery ends of these channels register with alternate consecutive spacer bars 179 on the cross conveyor 180. Associated with each of the channels or guides 177 and 178 is a yieldable retarder 181 in the form of a spring which slows up the rapid motion of the respective books and forces each match book to the inner face of its guiding channel for proper delivery into the space next adjacent the dividing bar 179 with which the inner side of the channel is registered.

The means for propelling the match books from receptacles 108 of the conveyor to the proper spaces in the cross conveyor comprise the ejectors or unloading arms 183 and 184, the latter being slightly elongated because of the greater radius of the guide channel 178 with which it coacts. The ends of these arms are bifurcated to be received over the match book retaining clips 107 of the receptacles 108 on conveyor F. Arms 183 and 184 are normally retracted and remain retracted during each advance of the conveyor over sprockets 140 and 139. During the dwell of conveyor F arms 183 and 184 are actuated rapidly to eject books from the receptacles registered with each of the unloading stations and to propel these books into the cross conveyor in opposite directions so that the smaller end of one book will lie opposite the larger end of the adjacent books on the cross conveyor.

Arms 183 and 184 are mounted on rock shafts 185 and 186 respectively, these shafts being interconnected by gearing 187 and operated through

rack 188 and pinion 189 from a cam 190 mounted on the main drive shaft 45. The cam groove 191 is concentric with the shaft 45 throughout a major portion of its periphery to hold arms 183 and 184 in their normally retracted positions aforesaid. There is also a slight concentric portion of the cam groove at 191 which causes a very brief period of dwell at the moment of delivery of the respective match books into their appropriate spaces in the cross conveyor 180 in order to make sure that their speed of delivery to the cross conveyor will not cause them to pass beyond it. Rack 188 carries the usual cam follower roller at 192 and may conveniently be guided on the main drive shaft 45 as shown in Fig. 11.

The cross conveyor 180 is in continuous operation, being driven from the main drive shaft 45 through gears 194, 195, chain 196, and shaft 197 as shown in Figs. 1, 2, 10 and 12. The conveyor 180 moves adjacent the counting and stacking table 200 upon which there is a curved guide 201 for forcing the match books into a more compact relation before their delivery to the discharge chute 202 (Fig. 10).

The counting and stacking arm is shown at 205. It is biased by means of a rope 206 and counterweight (or otherwise) to a normally retracted position against the stop 207. It is loosely pivoted at 208 for oscillation from its normally retracted position. Periodically it is oscillated through a wide arc about its fulcrum at 208 as a result of engagement by the roller 209 which revolves on arm 210 about the axis of the continually rotating shaft 211. Shaft 211 receives motion from the cross conveyor drive shaft 197 through the bevel gearing at 212, jack shaft 213, and chain 214.

During the dwell of the counting and stacking arm 205 the movement of cross conveyor 180 therebeneath will cause the accumulation of a predetermined number of match books within the range of movement of the arm 205. The timing accomplished by the driving connections to shaft 211 is such that when a predetermined number of match books lie within the sweep of arm 205 the roller 209 will strike arm 205 to oscillate it about its fulcrum 208, whereby to sweep the match books from the cross conveyor laterally over the stacking table 200 where the several books will be compacted owing to the constricting action of the guide member 201 on said table. In the final position of arm 205 as shown in dotted lines in Fig. 10, the stack of match books will have been delivered into the mouth of the discharge chute 202 for boxing.

The range of outward movement of the arm 205 is determined by the radius and position of movement of the roller 209. In its revolution about shaft 211 the roller 209 ultimately clears the arm, thus allowing the arm to be retracted by its biasing weight.

During its outward oscillation, the arm 205 passes beneath the fixed arm 219 and, in riding on the upper surface of guide member 201, the bar 205 lifts the switching pawl 220 to the dotted line position shown in Fig. 13 and passes therebeneath. After the passage of the arm 205 the switching pawl drops to its full line position in said figure and hence, after the roller 209 has swung to a position where it clears the arm, and the arm is drawn rearwardly by the biasing weight or rope 206, the arm will ride on to the upper surface of the switching pawl 220 and hence will be carried by the upper surface of the

fixed member 219 across the match books already advancing on the continuously moving conveyor 180. The stacking arm 205 thereupon falls by gravity to the position shown in Fig. 10 and Fig. 13, where it is aligned with the match books to sweep them from the cross conveyor when the arm is next engaged by the revolving roller 209.

The general organization of my improved match book machine has been described near the beginning of this specification, and in connection with the detailed description of each of its component parts I have described the operation of such part, indicating particularly the novel features thereof and those already known.

15 I claim:

1. In a match book machine, the combination with means for severing blanks from match combs, of match comb feeding means including rolls provided with continuously operable driving connections and frictionally operable upon match combs for the longitudinal advance thereof across the path of said severing means, and a stop for limiting said advance at a point appropriate for the severing of a blank from the match comb fed by said means said feeding means being operable at a rate in excess of that required for the advance of match combs to the blank severing means whereby to assure the determination of the size of the blank by engagement of the end of the comb with said stop and to provide a dwell at said stop for the operation of said severing means.

2. In a match book machine, the combination with comb severing means, of a guideway provided with a path for longitudinal comb travel to said means, a set of friction rolls yieldably mounted with reference to said guideway for the advance of a match comb thereon, and a stop positioned beyond said severing means, whereby to arrest the movement of a comb at a point appropriate to define the size of the blank to be cut therefrom by said severing means, said rolls being adapted to slip on the surface of the comb so arrested, means for continuously driving said rolls, and a feed means on which successive combs are movable beneath one of the rolls in a direction axially of the roll and laterally of the comb.

3. In a match book machine, the combination with a blank severing device and a stop adjacent thereto, of a guideway leading to said device in the direction of said stop, a set of yieldably mounted friction rolls mounted along said guideway in the path of match combs fed thereon for the frictional advance of such combs, certain of said rolls having a tapered end portion, and means for automatically introducing the butt portion of a match comb laterally beneath the tapered portion of said last mentioned roll to be advanced thereby along said guideway to said stop and means for actuating said last roll at a rate to assure contact of the comb with the stop in advance of each severing operation.

4. In a match book machine, the combination with a comb severing device and a stop limiting comb movement therebeyond to define the size of a blank to be severed by said device, of a comb feed guideway leading to said device, a set of frictional feed rolls disposed along said guideway in positions to advance a comb longitudinally thereon and means for intermittently actuating said rolls in a comb advancing direction to an extent in excess of the amount required to compensate for the length of the blank severed by said device, and means for depositing combs in-

75 intermittently upon said guideway, the rate of advance thereof being sufficient to enable each successive comb to overtake upon said guideway the end of the comb previously deposited thereon, whereby said combs are fed continuously to said stop to be acted upon by said severing device.

5. In a match book machine, the combination with a comb cut-off device, of a guideway for delivering combs longitudinally thereto, a stop 10 beyond said device for limiting movement of combs beyond said device, whereby to determine the length of the blank to be cut therefrom, friction rolls positioned along said guideway for the advance of combs thereover, a comb magazine beside said guideway, an ejector associated with said magazine and provided with means for its intermittent actuation in a direction to deliver combs laterally from said magazine to said guideway for friction propulsion by said rollers, and 20 means for operating said rollers at a rate in excess of the movement required to advance the combs for the distance of the blank severed therefrom, whereby each successive comb deposited by said ejector upon said guideway is advanced with such rapidity as to overtake the comb previously deposited thereon, the subsequent excess movement of said rolls being absorbed by slippage thereof upon the combs.

6. In a match book machine, the combination 30 with a match comb magazine and means for ejecting match combs successively therefrom in a direction laterally of the comb, of a match comb feeder positioned to receive the match comb from the ejector and including impositive 35 feeding means acting longitudinally upon the comb at a rate in excess of the removal of blanks, a stop in the path of a comb advanced by said feeding means, and a cut off knife provided with means for actuating it periodically to sever a 40 blank from a comb engaged by said stop, said stop being spaced beyond said knife at a distance equalling a number of splints of said comb.

7. In a match book machine, the combination with a match comb magazine and a match comb 45 ejector, of a feeder comprising a guideway for combs and means for the frictional driving of an ejected comb in a longitudinal direction of advance said driving means being located at one side of said guideway in a position to act solely 50 on the solid backs of successive combs, a stop against which the end portions of successive combs are held by said frictional driving means, and means including a cutter in spaced relation to said stop for severing blanks with a uniform 55 number of splints from the end portions of combs abutting the stop.

8. In a match book machine, the combination with a stop and a cut off knife in spaced relation thereto, of a feeder including a table leading to 60 said stop, a friction roll associated with the table and having a tapered end portion, said roll being rotatable in a direction to advance match combs longitudinally toward the stop at a rate exceeding the rate of severing blanks from successive 65 combs, whereby to assure comb engagement with the stop in advance of the operation of the knife, a magazine conveyor adjacent the table and an ejector associated with the conveyor and including means for pushing successive combs laterally 70 from the conveyor beneath the tapered end of said feed roll to be fed longitudinally thereby to said stop and knife.

9. In a match book machine, the combination with a stop and a cut off device in predeter- 75

mined relation to the stop, of a feed table leading to said stop, and feed means for advancing match combs longitudinally over said table directly toward said stop and cut-off device, said

5 feed means being located wholly adjacent one side of the path of travel of match combs over said table toward said stop, said feeding means including frictional devices adapted to permit said combs to come to rest against said stop.

10 10. In a match book machine, the combination with a feed table for match combs, of a stop limiting movement of match combs over said table, a cut off knife operable in predetermined spaced relation to the stop transversely of the 15 table for severing blanks from the successive end portions of match combs and feed rolls disposed wholly at one side of the path of match combs over said table and comprising rolls for acting frictionally solely upon the margins of such 20 combs for the advance thereof longitudinally over said table directly toward said stop and said knife.

11. In a match book machine, the combination with a feed table for match combs, of a stop 25 limiting movement of match combs over said table, a cut off knife operable in predetermined spaced relation to the stop for severing blanks from the successive end portions of match combs, and feed rolls disposed wholly at one side of the 30 path of match combs over said table and comprising rolls for acting frictionally solely upon the margins of such combs for the advance thereof toward said stop, said rolls being tapered toward the ends, together with means for feeding 35 combs transversely of said table beneath the tapered ends of said rolls.

12. In a match book machine, the combination with a feed table for match combs, of a stop 40 limiting movement of match combs over said table, a cut off knife operable in predetermined spaced relation to the stop for severing blanks from the successive end portions of match combs, and feed rolls disposed wholly at one side of the 45 path of match combs over said table and comprising rolls for acting frictionally solely upon the margins of such combs for the advance thereof toward said stop, said rolls being tapered toward the ends, together with means for feeding combs transversely of said table beneath the tapered 50 ends of said rolls, and a magazine conveyor arranged to deliver match combs successively to said transverse feeding means.

13. In a match book machine, the combination with a shear knife and means for intermittently 55 operating said knife across the path of a match comb, of a stop spaced beyond the knife in the path of comb advance for positively limiting the advance of match combs beneath said knife, and a frictional feeding device for advancing match combs longitudinally toward the stop and provided with means for continuously operating it at a rate sufficient to advance the comb between operations of the knife for a distance exceeding the space from the knife to the stop, whereby to 60 fix the length of the severed blank with reference to the stop independently of variations in the length of the comb.

14. In a match book machine, the combination with a feed table for the longitudinal delivery of 65 match combs, of a cut off knife periodically operable across the path of combs on said table, a stop spaced beyond said knife in said path for a

distance exactly equaling the width of a pre-determined number of splints of the blank to be severed from an advancing comb, and substantially continuously operable comb feeding means for advancing combs longitudinally across said 5 table to said stop, said means providing for lost motion and operating at a rate to impel the comb to the stop between successive operations of said knife for dwell against said stop during the operation of said knife and said knife being operable 10 during such dwell and during continued motion of the feeding means, whereby the width of the blank severed by the knife is entirely dependent upon the spacing of the stop from the knife independently of variations in length of the comb as 15 a whole.

15. In a match book machine, the combination with a match comb magazine comprising a first conveyor for match comb delivery, of means for severing blanks from successive combs, a second 20 conveyor including means for advancing combs longitudinally to said blank severing means, and mechanism for transferring combs from the first conveyor to the second conveyor, said magazine comprising supports exposed to receive match 25 combs for delivery by said first conveyor and second conveyor to said cut-off means.

16. In a match book machine, the combination with means for severing blanks from match combs, of a stop adjacent said severing means, a 30 conveyor arranged to deliver match combs longitudinally to said stop, a magazine comprising a conveyor with exposed match comb supports, means for actuating said conveyor to bring match combs supported thereby successively toward the 35 conveyor first mentioned, and ejector means for delivering match combs from their respective supports laterally to the conveyor first mentioned for delivery thereby to the severing means.

17. In a match book machine, a match comb 40 magazine comprising endless conveyor means, upper and lower guide means therefor between which a flight of said conveyor means extends in an upright direction, supports carried by said flight and exposed to receive match combs, a 45 table past which said flight extends, means for ejecting match combs from successive supports laterally on to said table, frictional driving means for feeding longitudinally over said table the match combs delivered thereto, a stop in the path 50 of combs fed by said frictional driving means, and comb severing means including mechanism for operating said severing means periodically across the path of a comb engaging said stop, whereby to sever a blank of predetermined length 55 therefrom.

18. In a match book machine, the combination with a device for feeding successive match combs, of a stop in the path of match combs fed by said device, a cutter in spaced relation to the stop and including means for periodically severing blanks from the match combs engaged with said stop, a conveyor having a flight provided with spaced match comb supports, and guides therefor, whereby said flight extends past said comb feed device in a position to register successive supports laterally with said device, an ejector for delivering successive combs from successive supports to said device to be fed thereby toward said stop, and means for actuating said ejector in synchronization with the movement of said conveyor. 60 65 70

EDWIN J. BELL.
